UNITED STATES PATENT OFFICE.

FRANK B. SHEA, OF BROOKLYN, NEW YORK.

BLANKET HOLDER FOR PRINTING CYLINDERS.

Application filed March 17, 1927. Serial No. 175,951.

My invention relates to blanket holders for printing cylinders and has for its object to provide a holder which will subtract a very small area from the printing surface of the cylinder and at the same time provide a simple, efficient and readily accessible securing means.

As is well known, certain cylinders of printing presses are covered with blankets which must be stretched tightly about the surface of the cylinder. Heretofore the means for securing a blanket to a cylinder have taken up an excessive area of the cylinder surface. This area represents a total loss of printing surface and results in the wide blank spaces on the printed sheet. In the case of a large web press with its many impression cylinders and through which large quantities of paper are passed, the space lost by the holding means amounts to a large total which adds materially to the expense of the output.

Heretofore in order to reduce this space to a minimum accessibility of the holding means has had to be sacrificed. It is an object of my invention to provide a holding means which will reduce waste space on the cylinder without sacrificing accessibility.

Another object of my invention is to provide a blanket holder which may be readily applied to or removed from a cylinder.

With these and other objects in view which will appear hereinafter I shall now describe a preferred embodiment of my invention and point out the novelty and scope of my invention in the appended claims.

In the accompanying drawing, Figure 1 is a view in cross-section of a printing cylinder provided with my improved blanket holder, the section being taken on a line 1—1 of Fig. 3.

Fig. 2 is a view in section similar to Fig. 1, but showing my improved holder in a different position; and

Fig. 3 is a side view of a printing cylinder partly broken away along the line 3—3 of Fig. 1 to illustrate my improved blanket holder in side elevation.

In the accompanying drawings I have used the reference numeral 10 to designate a printing cylinder. A notch 11 is cut in the face of the cylinder parallel to the cylinder axis. One wall 12 of the notch is preferably radial to the cylinder. Bearing against the wall 12 is a plate 13 which is held in place by means of headed pins 14. The

latter pass through slots 15 in the plate 13. If desired the pins 14 may be threaded into the wall 12, but I prefer to attach them to a rail 16 which is seated in an undercut longitudinal slot 17 formed in the wall 12. The slot and the rail are preferably of dove-tail in cross section, so that the rail will be locked against lateral movement, but may slide endwise in the slot. The outer end of the rail 16 carries a lug 18 through which a screw 19 is passed and threaded into the cylinder, thereby locking the rail and the pins it carries to the cylinder.

Secured to the plate 13 at suitable intervals by means of straps 20 are springs 21. These springs are preferably of rectangular cross-section so that they will not turn in the straps 20. The springs are of inverted V shape with the free ends curved outwardly and forming feet 22 which engage a slot 23 in the bottom of the notch 11. The springs 21 tend to hold the plate 13 in the raised position shown in Figures 1 and 3, and in this position the pins 14 engage the bottoms of the slots 15. When the plate 13 is in a raised position it projects from the peripheral face of the cylinder so that hooks 24, projecting from the exposed face of the plate 13, are readily accessible. A blanket

25 is coiled about a roller 26 lying within the notch 11 and passes around the cylinder 10 with its free end engaging the pins 24. It will be observed that the slots 15 are of bayonet form comprising in each case a vertical portion terminating at the outer end in a lateral offset 27. The offsets 27 are

rounded at the bottom to provide seats for the pins 14 and at the juncture of these rounded bottoms with the vertical portions 95 of the slots there are slightly raised points or shoulders 28. Thus when the plate 13 is depressed so that its outer edge lies slightly below the peripheral face of the cylinder 10 the plate may be moved laterally to permit the pins to enter the offsets 27. Then on releasing the plate the springs 21 will raise the plate, so that its outer edge lies flush with the peripheral face of the cylinder, and the shoulders 28 will hold the pins in

the offsets 27 preventing endwise movement of the plate.

At one end of the plate 13 there is a projection or ear 29 which is preferably rounded at the lower edge thereof. Mounted on the wall 12 is a spring 30 which is downwardly curved in the path of the projection 29.

Thus, when the plate 13 is depressed the rounded edge of the ear 29 engages the spring 30 and the latter presses the plate 13 endwise, so that as soon as the pins 14 clear the shoulders 28 the plate 13 will be automatically moved endwise, permitting the pins to enter the offsets 27 and lock the plate in depressed position.

In practice whenever it is desired to attach or detach a blanket from the cylinder the plate 13 is slightly depressed and moved endwise against the tension of spring 30 to permit the pins 14 to clear the offsets 27, whereupon the springs 21 will force the plate 13 outward to the position shown in Figures 1 and 3. The end of a blanket may then be attached to or detached from the hooks 24 which now are in a position of ready accessibility. After a blanket has been attached to the plate and the plate is forced down into the notch 11 the spring 30 will automatically push it endwise in position to be locked by engagement of the pins 14 with the offsets 27. Thereafter the take-up roller 26 is turned to take up any slack in the blanket. The construction of the take-up roller forms no part of my invention and may be of any well-known form.

It will be observed that by my invention the holding plate 13 is disposed radially with respect to the cylinder and thus occupies a minimum space. Hence the width of the slot 11 may be such that the pins 24 on the plate will just clear the blanket wound up on the take-up roller 26.

While I have illustrated and described a preferred embodiment of my invention, I consider myself at liberty to make such changes in construction, form and arrangement of various parts as fall within the definition of the following claims:

I claim:

1. In combination with a printing cylinder having an axially disposed notch formed in the periphery thereof, attaching means within the notch to which one end of a blanket may be secured, means in the notch by which the opposite end of the blanket may be drawn taut, said attaching means being mounted to slide substantially radially without the notch, and means for locking said attaching means in depressed position.

2. In combination with a printing cylinder having an axially disposed notch formed in the periphery thereof, a blanket holder comprising a plate mounted to slide inwardly and outwardly in the notch, attaching means carried by the plate, a spring tending to force the plate outward, whereby the attaching means will project beyond the peripheral face of the cylinder, and means for locking the plate in depressed position.

3. In combination with a printing cylinder having an axially disposed notch formed in the periphery thereof, a blanket holder com-

prising a plate mounted to slide radially in the notch, hooks carried by the plate, a spring tending to force the plate outward, whereby the hooks will project beyond the peripheral face of the cylinder, and means for locking the plate in depressed position.

4. In combination with a printing cylinder having an axially disposed notch formed in the periphery thereof, a plate mounted to slide radially in the notch, hooks carried by the plate and adapted to engage one end of a blanket, a spring tending to force the plate outward, whereby the hooks will project beyond the peripheral face of the cylinder, means for locking the plate in depressed position and a take-up roller in the notch about which the opposite end of the blanket may be wound.

5. In combination, a printing cylinder formed with an axially disposed notch in the periphery thereof, the notch having a substantially radial wall, a plate, hooks carried by the plate, means for holding said plate in radially slidable engagement with said wall, a spring tending to force the plate outward to a position in which the hooks will project beyond the peripheral face of the cylinder, and means for locking the plate in depressed position.

6. In combination, a printing cylinder formed with an axially disposed notch in the periphery thereof, the notch having a substantially radial wall, a plate, formed with bayonet slots, headed pins engaging the slots respectively and securing the plate in radially slidable engagement with said wall, hooks carried by the plate, a spring tending to slide the plate outward to a position in which the hooks will project beyond the peripheral face of the cylinder, and means tending to press the plate endwise when the plate is depressed, whereby the pins will enter the offset portions of the bayonet slots and lock the plate in depressed position.

7. In combination, a printing cylinder formed with an axially disposed notch in the periphery thereof, the notch having a substantially radial wall, a plate formed with bayonet slots, headed pins engaging the slots respectively and securing the plate in radially slidable engagement with said wall, hooks carried by the plate, the bottom of the notch being formed with a groove, a V shaped spring, means for securing the spring to the plate, the free ends of the spring engaging the groove and tending to slide the plate outward to a position in which the hooks will project from the peripheral face of the cylinder, and another spring tending to press the plate endwise when the latter is depressed, whereby the pins will enter the offsets of the bayonet slots and lock the plate in depressed position.

8. In combination, a printing cylinder formed with an axially disposed notch in

the periphery thereof, the notch having a substantially radial wall, a plate formed with slots, headed pins engaging the slots respectively and securing the plate in radially slidable engagement with said wall, hooks carried by the plate, a spring tending to slide the plate outward to a position in which the hooks will project beyond the peripheral face of the cylinder, each of said 5 slots having a radial portion and a lateral offset at the outer end of the radial portion and an outwardly projecting shoulder at the junction of the radial portion and the offset, and means for causing the plate to move endwise when it is depressed, whereby the pins 10 will enter said offsets, holding the plate in depressed position and the shoulders will lock the plate against endwise movement.

9. In combination, a printing cylinder 20 formed with an axially disposed notch in the periphery thereof, a plate formed with bayonet slots, headed pins engaging the slots respectively and securing the plate in slid- 25 able engagement with one of the side walls of said notch, hooks carried by the plate, a spring tending to slide the plate outward to a position in which the hooks will project beyond the peripheral face of the cylinder, the plate being formed at one end with a project- 30 ing ear, and another spring mounted in the notch in the path of said ear, whereby when the plate is depressed the latter spring will engage the ear, tending to move the plate end- 35 wise so that the pins will enter the offset por- tions of the bayonet slots and lock the plate in depressed position.

10. In combination, a printing cylinder 40 formed with an axially disposed notch in the periphery thereof, the notch having a sub- stantially radial wall, a plate formed with

bayonet slots, headed pins engaging the slots respectively and securing the plate in radially slidable engagement with said wall, hooks carried by the plate and adapted to engage one end of a blanket, a take-up roller 45 in the notch about which the other end of the blanket is adapted to be wound, a spring tending to slide the plate outward to a position in which the hooks will project beyond the peripheral face of the cylinder, the 50 plate being formed at one end with a projecting ear, and another spring mounted in the notch in the path of said ear, whereby when the plate is depressed the latter spring will engage the ear tending to move the 55 plate endwise so that the pins will enter the offset portions of the bayonet slots and lock the plate in depressed position.

11. In combination, a printing cylinder 60 formed with an axially disposed notch in the periphery thereof and with an undercut groove in one of the side walls of the notch, a rail slidable endwise in the groove, means for securing the rail in fixed position in the groove, a plate formed with bayonet slots, 65 headed pins engaging the slots respectively and securing the plate in slidable engage- 70 ment with the rail, hooks carried by the plate, a spring urging the plate outwardly to a position in which the hooks will project from the peripheral face of the cylinder, and means for causing the plate to move end- 75 wise when it is depressed whereby the pins will enter the offset portions of the bayonet slots and hold the plate in depressed posi- tion.

In witness whereof, I hereby affix my signature this 16th day of March, 1927.

FRANK B. SHEA.
